UNITED STATES PATENT OFFICE.

MELVIN BENNINGTON, OF EVERETT, WASHINGTON.

MOP HEAD.

Application filed February 23, 1926. Serial No. 89,872.

This invention relates to mop heads, and its object is to provide a strong, simple and durable device of this kind that can be easily manipulated and cheaply manufactured.

With these and other objects in view, the invention consists of a novel combination and arrangement of parts which are herein-after described and set forth in the accompanying specification and drawings, where-
10 in—

The figure is a perspective view of the device showing the construction and method of operation.

Referring more in detail to the drawings, 15 the numeral 1 designates the handle 2 and 3 the nuts and bolts by means of which the handle is secured to the mop head frame 4. The mop head frame 4 is composed of a strap of metal having a cross bar 5 secured 20 rigidly into the sides of the frame. Slots 6, 7, 8 and 8' are cut into the cross bar 5 and into the bottom of the frame 9. A movable jaw composed of a rod 10 with its 25 ends 11 and 12 bent at an angle of approxi- mately 80 degrees and inclined toward one another is mounted movably in the frame by means of the slots therein.

The ends of the jaw 10 are threaded to 30 receive wing nuts 13 and 14 by means of which the jaw is raised and lowered in refer- ence to the bar 9.

The operation of the device is as follows: In order to insert the mop the wing nuts 13 and 14 are turned until the jaw is sufficiently opened to permit the insertion of the mop. 35 The nuts are then turned in the opposite direction to draw the jaw tightly against the bottom bar 9 and thus hold the mop securely in position. When in this position the tops of threaded ends of the jaw rest 40 against the sloping sides of the frame and are thus prevented from becoming entangled in the mop as it is used.

Having thus described my invention, what I claim as new therein and desire to secure 45 by Letters-Patent, is:

In a device of the character described, a 50 mop head comprising a stationary frame, a cross bar secured rigidly in said frame, said frame and cross bar being provided with slots, a movable jaw comprising a rod having its end portions bent to incline at a slight angle toward one another, the end 55 portions being threaded and disposed through the slots of the frame and the cross bar, and nuts on the threaded ends of the jaw, by means of which the jaw is raised and lowered.

Signed at Everett, Snohomish County, 60 Washington, this 16th day of February, 1926.

MELVIN BENNINGTON.
